UNITED STATES PATENT OFFICE.

BURT A. PETERSON, OF ROCKFORD, ILLINOIS, ASSIGNOR TO HOWARD D. COLMAN, LUTHER L. MILLER, AND HARRY A. SEVERSON, COPARTNERS DOING BUSINESS AT ROCKFORD, ILLINOIS, AS BALBET-COLMAN COMPANY.

APPARATUS FOR FACILITATING THE LOADING OF BOBBIN-MAGAZINES.

1,062,250.

Specification of Letters Patent.

Patented May 20, 1913.

Application filed December 2, 1910. Serial No. 595,228.

To all whom it may concern:

Be it known that I, BURT A. PETERSON, a citizen of the United States, residing at Rockford, in the county of Winnebago and 5 State of Illinois, have invented certain new and useful Improvements in Apparatus for Facilitating the Loading of Bobbin-Magazines, of which the following is a specification.

10 This invention relates to bobbin magazines as, for instance, those provided for portable spinning-frame doffers, and refers particularly to means for facilitating the 15 operation of loading such magazines with bobbins.

In the accompanying drawings, Figure 1 is a side elevation of one form of apparatus embodying my invention. Fig. 2 is a front elevation of said apparatus. Fig. 3 illustrates the apparatus in top plan. Fig. 4 is a sectional view through the magazine support, the view being taken in the plane of dotted line 4-4 of Fig. 6. Fig. 5 is a sectional view on dotted line 5-5 of Fig. 4. 25 Fig. 6 is a section on line 6-6 of Fig. 4.

The form of magazine herein shown by way of example consists of vertical walls *a b c d*, a removable bottom-closure comprising two cross wires *e*, and vertical partitions *f g* adapted to confine the contained bobbins in tiers, the upper end of the magazine being open. It will be seen that the partitions *f g* divide the magazine into compartments each of sufficient width to contain 35 a single bobbin.

That embodiment of the invention which is herein illustrated comprises a supporting frame 1 and a horizontal table 2 bounded at its side and rear by walls 3. Means is provided for supporting a magazine in such relation to the table that bobbins piled upon the table may be conveniently placed in proper order in the magazine. In the construction herein shown, there is formed in 45 the table 2 an opening 4 adapted to receive a magazine, and means is provided below the table for supporting the magazine with its open upper end substantially flush with the surface of the table. Said supporting 50 means may consist, as herein shown, of a platform 5 rigidly secured in the frame 1 in a suitable manner.

Each of the bobbin compartments being of considerable height, it will be understood

that if a bobbin were placed in the upper 55 end of a compartment and permitted to drop to the bottom of the magazine, said bobbin might turn in falling and fail to assume a horizontal position, or might be laterally displaced out of its proper compartment. I 60 therefore provide means for reducing the fall of the bobbins to such an extent that they cannot become disarranged. This means, in the present embodiment, comprises bobbin-supporting members 6, each of sufficient width to properly support a bobbin, of suitable thickness for insertion into a bobbin compartment, and of such height as to reduce the fall of the bobbin in its compartment to the desired extent. Each member 6 is slotted as at 7 to pass the wires *e*. The members 6 are secured together at their lower ends in spaced relation, in any suitable manner, as by being formed integral with a base 8. The platform 5 has an 75 opening 9 therein through which the members 6 extend. In order that the members 6 may recede downwardly as bobbins are loaded into the magazine, I provide suitable means, as, for example, a carrier 10 on 80 which the group of members 6 is located, said carrier being supported for vertical movement by means of flexible connections 11 extending over sheaves 12 attached to the lower side of the table 2, said connections bearing counterweights 13. The carrier 10 is guided in its vertical movements by rods 14 fixed to the carrier and extending slidably through brackets 15 fixed to the platform 5 and through openings 16 in 90 said platform. Downward movement of the carrier 10 may be limited in any suitable way, as by the engagement of projections 17 on the rods 14 with the upper brackets 15, upward movement being limited by contact 95 of the carrier with the lower brackets 15. In the present instance the carrier 10 is slightly overbalanced so that it tends to rise. Upon the lower side of the carrier is fixed a loop 18 which may be engaged by the 100 foot of the operator to depress or assist in depressing the carrier as the loading progresses.

In use, a quantity of bobbins is placed upon the table 2 and an empty magazine 105 inserted through the opening 4 until it rests upon the platform 5, the members 6 extending upwardly in the compartments of

the magazine to a point near the top thereof. Bobbins are then taken from the table by the operator and placed in the compartments, the members 6 serving as an adjustable false bottom on which the bobbins rest as the growing mass of bobbins in the magazine settles. When the magazine is fully loaded, the members 6 have descended until their upper ends are substantially flush with the wires e. It will be seen that the members 6 permit of loading bobbins into the relatively deep magazine in proper order. When the magazine is filled it is lifted out of the opening 4, recesses 4^a being formed in the sides of the opening in order to enable the operator to grasp the upper end of the magazine.

While the magazine herein illustrated is adapted to contain warp bobbins, it will be understood that the apparatus may be adapted to load filling bobbins by making the members 6 of suitable dimensions to enter the compartments of a filling-bobbin magazine.

25 I claim as my invention:

1. An apparatus for facilitating the loading of bobbin magazines comprising a support for a bobbin magazine, and a false bottom for a magazine placed on said support, 30 said bottom being movable toward and away from the inlet end of the magazine.

2. An apparatus for facilitating the loading of bobbin magazines comprising means for supporting a bobbin magazine with its inlet end uppermost, and a false bottom vertically movable within a magazine placed on said supporting means.

3. An apparatus for facilitating the loading of bobbin magazines comprising a support for a bobbin magazine having a plurality of compartments therein, a plurality of bobbin-supporting members insertible into the magazine through the end opposite its inlet end, each of said members being adapted to enter one of said compartments, and means for supporting said plurality of members for movement toward and away from the inlet end of the magazine.

4. An apparatus for facilitating the loading of bobbin magazines comprising a support for a bobbin magazine, said support having an opening therein, a carrier movable toward and away from the support, and bobbin-supporting means on said carrier, which means is adapted to pass through

said opening and enter a magazine placed on said support.

5. An apparatus for facilitating the loading of bobbin magazines comprising a support for a bobbin magazine, a carrier, guide sheaves, flexible connections attached at one end to said carrier and extending over said sheaves, weights attached to the other ends of said connections, and bobbin-supporting means mounted on said carrier and adapted to support bobbins placed in a magazine set upon said support.

6. An apparatus for facilitating the loading of bobbin magazines comprising a table having an opening therein to receive a bobbin magazine, and a support below said opening to support the magazine with its inlet end substantially flush with the table, a carrier below said support, means for supporting said carrier for vertical movement, 75 and bobbin-supporting means mounted on said carrier and adapted to enter the lower end of a magazine set upon said support.

7. An apparatus for facilitating the loading of bobbin magazines comprising a table 80 having a bobbin-supporting space and an opening in front of said space to receive a bobbin magazine, a support below said opening to support the magazine with its inlet end substantially flush with the table, and bobbin-supporting means vertically movable into and out of a magazine set upon said support.

8. An apparatus for facilitating the loading of bobbin magazines comprising a support for a bobbin magazine, said support having an opening therein, a carrier below said support and movable vertically toward and away from said support, and bobbin-supporting means on said carrier adapted 95 to pass through said opening and enter the magazine.

9. An apparatus for facilitating the loading of bobbin magazines comprising a support upon which a bobbin magazine may be 100 removably set, and means movable lengthwise of the magazine, and into and out of the latter, for temporarily supporting bobbins in the magazine.

In testimony whereof I affix my signature in the presence of two witnesses.

BURT A. PETERSON.
